SHEET FEEDING MECHANISM

Robert J. Thompson, Harrisburg, Pa., assignor to
 The W. O. Hickok Mfg. Co., Harrisburg, Pa.,
 a corporation of Pennsylvania

Application June 9, 1947, Serial No. 753,483

25 Claims. (Cl. 164—87)

1

This invention relates to a sheet feeding mechanism, and more particularly to a mechanism for feeding paper sheets to a perforator.

There is in common use a rotary paper perforator having parallel shafts one of which carries discs having projecting perforator pins or fingers and the other of which carries a disc having openings to receive the perforating pins, the paper or other sheets to be perforated being fed between such sets of discs. In the use of such apparatus, it is the common practice to feed the sheets manually in groups of two or more. The reason for this is that the perforator will more cleanly punch holes in a plurality of sheets than in a single sheet, the number of sheets fed to the apparatus depending upon the nature and thickness of the individual sheets.

The reason for the manual feeding of sheets to perforators of the type referred to lies in the fact that sheets are commonly fed to the machine in groups of two or more instead of singly, and so far as I am aware, no practical machine has ever been developed for automatically collecting a predetermined number of superposed, registered sheets and then feeding them to the perforator. Accordingly operators gather and register a number of sheets and feed them by hand through the apparatus, and the perforations are thus cut much more cleanly than can be done with a conventional sheet feeder wherein single sheets are fed to the perforator. At the same time, the manual feeding of an apparatus of this character is obviously far more costly than would be true with the use of a mechanical device for gathering and feeding the sheets in predetermined numbers to the perforator.

An important object of the present invention is to provide an apparatus which is automatically operative for gathering and registering a predetermined number of sheets of material and then feeding them forwardly to a perforator or other apparatus adapted to perform operations on such a plurality of sheets.

A further object is to provide an apparatus of the character referred to which is fully automatic for collecting successive single sheets fed thereto, arresting the sheets until a predetermined number has been gathered, and then automatically feeding such group of sheets to a machine such as a perforator.

A further object is to provide such an apparatus wherein, in addition to the functions just referred to, the sheets making up each individual group are jogged laterally and longitudinally to accurately register them before feed-

2

ing them to the perforator or other work-performing machine.

A further object is to provide such an apparatus which is readily adjustable within limits for the collection of any desired number of sheets, depending upon the nature and thickness of the individual number of sheets, before feeding them to the work-performing machine.

A further object is to provide an apparatus of this character which is likewise adjustable to take care of sheets of varying widths and lengths, thus rendering the apparatus universally adaptable for the feeding to a perforator or other work-performing machine sheets of any size which the work-performing machine is capable of operating on.

A further object is to provide such an apparatus wherein, upon the gathering of a predetermined number of sheets, such sheets are released 10 by a suitable gate to start the movement of the sheets through the work-performing machine, and to thereafter promptly close the gate on top of the group of sheets whereby succeeding sheets to form the next group may be fed 15 into the apparatus without awaiting the discharging of the previously formed group, thus rendering the apparatus highly efficient and making it possible to greatly increase the productivity of the perforator or the like as compared with the manual feeding thereof.

Other objects and advantages of the invention 20 will become apparent during the course of the following description.

In the drawings I have shown one embodiment 25 of the invention. In this showing

Figure 1 is a plan view of one end of the apparatus shown in conjunction with a conventional perforator.

Figure 2 is a side elevation of the apparatus, 30 shown in conjunction with a conventional perforator.

Figure 3 is a vertical section taken through the apparatus substantially on the line 3—3 of Figure 1 but showing the portions of the apparatus omitted in Figure 1, parts being broken away, 35 as indicated between the dot and dash lines.

Figure 4 is an enlarged fragmentary side elevation of a portion of one end of the apparatus adjacent the perforator, a portion of the control cam means of the latter being diagrammatically represented by broken lines.

Figure 5 is a plan view of the same, the cam mechanism being omitted.

Figure 6 is a section taken substantially on 50 line 6—6 of Figure 1.

Figure 7 is an enlarged transverse vertical sectional view on line 7-7 of Figure 5, parts being broken away.

Figure 8 is an enlarged fragmentary side elevation of the opposite side of the apparatus from that shown in Figure 4.

Figure 9 is a vertical section on line 9-9 of Figure 2, and

Figure 10 is a horizontal sectional view on line 10-10 of Figure 3, parts being broken away to contract the view both transversely and longitudinally.

Referring to Figures 1 and 2, the numeral 10 designates a conventional perforating mechanism as a whole in common use for perforating paper sheets and relatively thin sheets of other flexible material. Such perforator comprises a support 12 carrying a horizontal shaft 13 and supporting relatively heavy upper bearings 14 (Figure 1) in which is journaled an upper shaft 15. The shaft 15 carries a plurality of discs 16 having radially extending perforators 17 of conventional type generally illustrated in Figure 1. Inasmuch as the perforator mechanism is conventional, it is believed that the perforators 17 and other parts of the perforator generally need not be shown in specific detail. The lower shaft 13 carries discs 18, fragmentarily and diagrammatically represented in Figure 6, and it is understood that the discs 18 correspond in arrangement to the discs 17 and are provided with perforations for the reception of the perforators 17 as the two sets of discs are rotated.

Means (not shown) forming a part of the conventional perforator 10 is connected between the shafts 13 and 15 to drive the latter whereby the discs 16 and 18 are driven at the same peripheral speed and rotate in the direction of the arrows in Figure 6.

The perforator 10 includes conventional upper and lower feed rollers 24 and 25, also conventionally driven by means (not shown) so as to rotate in the direction of the arrows in Figure 6 at the same peripheral speed as the discs 16 and 18. The rolls 24 and 25 have their line of contact arranged approximately in the horizontal plane of the bed 27 of the perforator 10. It is the common practice for operators to manually gather and register a plurality of sheets and then feed such sheets manually between the rolls 24 and 25 and thus into the perforator. The parts previously described, as will be apparent, form conventional parts of a widely used type of perforator and form no part per se of the present invention.

The shaft 15 carries a relatively thick disc 30 (Figures 1 and 4) and in the inner side of this disc is provided a cut-away portion 31 forming a cam drop to control the feeding of the sheets to the perforator, in a manner to be described.

Outwardly of the disc 30 is arranged a plate or disc 35, utilized as a sprocket in a manner to be referred to, and against this disc is arranged a plurality of cams 36 protected and retained in position by a plate 37. As will be further described in detail below, the cams 36 control a conventional rotatable vacuum operated sheet feeding device for the present mechanism, each cam 36 being adapted to operate a suitable valve to result in the feeding of a sheet to the apparatus. At the point in the operation of the apparatus where a group of sheets is released and fed to the rolls 24 and 25, it is desirable to momentarily stop the feeding of the next sheet to the apparatus so that the previously collected

group of sheets can be started on their way to the perforator before the collection of the next group of sheets is started. For this reason, the cams 36 are equidistantly spaced except for a gap occurring in the embodiment illustrated approximately at the point indicated by the numeral 38 in Figure 2.

In the arrangement thus illustrated, five cams are employed, and in such case each group of sheets collected will comprise five sheets which will be fed to the apparatus at uniform intervals until the gap 38 is reached, at which point the feeding of one sheet will be skipped and the apparatus will function to automatically feed the collected group of sheets to the perforator. I have found it advisable to arrange the cams 36 an angular distance apart equal to 360° divided by the number of cams 36 plus one. In other words, where five cams are employed, such cams will be arranged angularly with respect to each other 360° divided by five plus one, that is, divided by six. Thus, except for the gap 38, the cams 36, where five are employed, will be arranged 60° apart.

Referring generally to the drawings, the numerals 42 and 43 designate a pair of parallel side rails projecting from the inlet side of the perforator. The ends of these side rails remote from the perforator are supported by the frame 45 of a conventional individual sheet feeding mechanism which need not be illustrated in detail. This mechanism is in common use with many paper working machines, for example ruling machines, and it will be understood that it comprises paper feeding strings 46 (Figure 2) ahead of the upper run of which is arranged a rotary vacuum head 47 of conventional type, positively driven (by means not shown) at a peripheral speed equal to the linear speed of the strings 46. When vacuum is connected to the head 47, a sheet in engagement therewith will be fed toward the left as viewed in Figure 2 and thus will enter the inlet end of the present apparatus, as will be referred to further below.

The vacuum head 47 has a vacuum pipe 50 connected thereto leading through a control valve 51 and another pipe 52 to a suitable source of vacuum (not shown). The valve 51 is operable by a stem 53 urged to closed or inoperative position by a spring 54. The rod 53 extends to a point in proximity to the cams 36 and is provided with a wheel 56 successively engageable by the cams 36. Thus it will be apparent that the cams 36 successively engage the roller 56 to move the rod 53 toward the right, as viewed in Figure 1, to momentarily energize the vacuum head 47 and thus initiate movement of another sheet into the present apparatus. The end of the rod 53 adjacent the perforator is supported in a bearing guide 57 referred to further below.

The ends of the side rails 42 and 43 adjacent the perforator are secured as at 60 (Figure 6) to side bearings 61 and 62 and these bearings rest upon and are supported by a projection 64 carried by the bed of the perforator, each bearing 61 being provided with an ear 63 (Figure 5) through which passes a machine screw or the like 63' for securing the bearings in position.

The projection 64 forms a conventional part of an ordinary perforator of the type referred to and is provided with a T-slot 65. The present invention makes use of such slot for receiving a bar 66 having an upper face 67 sloping downwardly slightly in a direction away from the perforator. The bar 66 is maintained in position by

heads 68 of screws connected to the bar 66, the heads 68 being arranged in the groove 65.

Above the bar 66 is arranged a shaft 70 journaled at its ends in the bearings 61 and 62. The shaft 70 carries a gate 71 normally occupying approximately the position shown in Figure 6 just above the surface 67 and just behind the shoulder 12 formed by the forward end of the slot 65 above the low side of the surface 67. In a manner to be described, successive sheets are fed in overlapped relation toward the left in Figure 6 until they contact with the gate 71, and when the predetermined number of sheets has been gathered, the gate 71 is opened and the sheets are fed toward the feed rolls 24 and 25 for engagement therewith.

At the side of the apparatus adjacent the bearing 62 (Figures 1 and 8) the shaft 70 is provided with a collar 75 carrying an integral projecting arm 76. One end of a spring 77 is connected to this arm and the other end of this spring is connected to an eye 78 carried by a tubular boss 79 secured to the adjacent bearing 62. The spring 77 is of the tension type and accordingly tends to turn the shaft 70 in a counterclockwise direction, as viewed in Figure 8, and in a clockwise direction, as viewed in Figure 4. The boss 79 carries an upwardly extending rubber bumper 80 against which the arm 76 is adapted to strike when it reaches its lowermost position after the shaft 70 is released in a manner described below.

Adjacent the end of the shaft 70 opposite the arm 76, that is, the end adjacent the disc 30 (Figure 1) the shaft 70 is provided with a collar 85 fixed thereto and this collar has one end of a rod 86 fixed thereto, the rod extending downwardly toward the disc 30, as shown in Figure 4.

The end of the rod 86 remote from the shaft 70 is engaged by the periphery of the disc 30 and is normally held thereby in the position shown in Figure 4, in which position the arm 76 occupies the position shown in Figure 8. When the cam drop 31 reaches the adjacent end of the arm 86, the latter is released to drop into the cut-away 31, the spring 77 thereupon rocking the shaft 70 in a clockwise direction, as viewed in Figures 4 and 6, to open the gate 71. This operation takes place with the cam gap 33 in proximity to the roller 56. As previously stated, the valve operating rod 53 is carried by the bearing 57. For convenience, this bearing may be supported by the shaft 70 and for this purpose has a depending portion 90 the lower end of which freely receives the shaft 70, the latter thereby being free to turn and acting for supporting the bearing 57.

The bearings 61 and 62 rotatably support the lower of a pair of cooperating shafts 100 and 101, the upper shaft 101 being parallel to the shafts 70 and 100 and being arranged between and free of the bearings 61 and 62 for bodily up and down movement in a manner to be described. The shaft 100 carries a sprocket 102 about which a chain 103 passes, and this chain, in turn, passes around a sprocket 104 carried by a shaft 105 forming a conventional part of the perforator. The chain 103 serves to drive the shaft 100 at the linear speed of the rolls 24 and 25, and the shaft 100 is, in fact, a feed roller for the incoming paper coming up against the gate 71, and the top limit of such roller 100, as shown in Figure 6, is approximately in the horizontal plane of the top of the bed 27.

The shaft 101 is journaled at its ends in bearing arms 110, these arms having portions 111

surrounding the shaft 101 and fixed thereto by set screws 111'. Upon the rocking of the shaft 70, therefore, the shaft 101 will be raised and lowered.

The shaft 70 carries a disc 115 adjacent each bearing arm 110, said disc being cut away as at 112 to form a shoulder 113. Each bearing arm 110 carries a laterally projecting lug 108 in which is threaded a screw 117 held in adjusted positions by a jam nut 116. Each screw 117 has its lower end contacting with the associated shoulder 113 and accordingly the shaft 101 is normally held in the upper position shown in Figure 6.

The shaft 101 carries a plurality of rubber or similar rollers 120. These rollers have their bottoms normally spaced above the shaft or roller 100 as shown in Figure 6, and accordingly paper is freed for movement between the roller 100 and the upper rollers 120 into engagement with the gate 71. When the rod 86 (Figure 4) drops into

20 the cut-out 31, the shaft 70 rocks in a clockwise direction as viewed in Figures 4 and 6 under the influence of the spring 77 (Figure 8) and the gate 71 opens in the manner previously described. When such operation takes place, the shoulders

25 113 move downwardly relative to the screws 117, thus releasing the bearing arms 110 for downward movement. This operation engages the rubber rollers 120 with the paper extending over the roller 100, thus pinching the paper between the roller 100 and rollers 120 to feed the paper through or past the open gate 71. When the cut-out 31

30 (Figure 4) passes beyond the adjacent end of the rod 86, at which time the advancing sheets will have been engaged by the rollers 24 and 25, the rod 86 will be moved radially outwardly relative to the disc 30 to restore the gate 71 to normal position. The gate is thus positioned to stop subsequent sheets fed thereagainst while at the same time permitting the previously gathered sheets to

35 be bowed downwardly under the closed gate 71 to be pulled therewith by the rollers 24 and 25.

Means are provided for supporting the sheets as they approach and engage the gate 71. Referring to Figures 5 and 6, the numeral 125 indicates a

40 stay rod connected between the side frame members 42 and 43 to brace them relative to each other. A part of the stay rod 125 also shows in Figure 7. A similar stay rod 126 is connected between the side frame members 42 and 43 at a point substantially spaced from the perforator, the stay rod 126 being shown in dotted lines in Figure 2 from which its general location may be readily ascertained. Each of the stay rods 125 and 126 carries a plurality of collars 128 fixed thereto by set

45 screws 129. Each collar 128 carries an upward projection 129 having flat tops lying in a common horizontal plane and engageable against the inside of inverted U-shaped elongated paper supporting members 130. These members may be

50 suitably formed of any material, for example, stainless steel or the like, and they form a relatively flat bed for the free movement of the paper thereover.

55 Adjacent one side of the apparatus, and preferably at the side toward the side frame member 43, one of the collars 128 is utilized for supporting a paper guide 135, preferably of angle iron section arranged as shown in Figures 7 and 9 and having its bottom flange arranged in the horizontal plane

60 of the tops of the paper supporting bars 130. The stay rods 125 and 126 being stationary, it will be obvious that all of the paper supporting bars 130 and the guide 135 are likewise stationary. A paper guide 136, similar to the guide 135, is arranged in

65 70 the position shown in Figures 1, 5 and 9 with its

horizontal flange in the horizontal plane of the paper supporting bars 130. The guide 136 is laterally moved or jogged by means to be described to assist in properly registering the paper sheets with each other.

A longitudinally movable jogger shaft 140 extends transversely in the apparatus adjacent and parallel to the shaft 125, and a similar jogger shaft 141 (Figures 1 and 3) is arranged adjacent the stay rod 126. Each of these jogger shafts extends through and is slidable in the side frame members 42 and 43 and each is pivotally connected as at 143 to one arm of a bell crank lever 144. Each of these bell crank levers is pivoted as at 145 on a bracket 146 carried by the side frame member 42.

The other arm of each bell crank lever 144 is pivotally connected as at 147 to a rod 148, and it is obvious that reciprocation of this rod rocks the bell crank levers 144 to move the jogger shafts 140 and 141 longitudinally thereof, that is, transversely of the apparatus. Each of the jogger shafts carries a collar 150, which may be identical with the collars 128 previously described, and the paper aligning or jogger guide 136 is secured to the upward projection 151 of each collar 150.

The roller shaft 109 is provided adjacent the sprocket 102 with a collar 155 (Figures 4 and 5) and this collar carries a projecting eccentric pin 156. This pin, in turn, is rotatable in one end of a link 158, and the opposite end of this link is pivoted as at 149 to the adjacent end of the rod 148. The shaft 109 is constantly driven by the chain 103, and accordingly the eccentric pin 156 constantly reciprocates the bar 148 to similarly constantly reciprocate the jogger guide 136 through the shafts 140 and 141. The collars 150, which secure the jogger 136 to the shafts 140 and 141, are adjustable along such shafts according to the width of the sheets to be perforated or otherwise treated, and the adjustment is so made that the distance from the vertical flange of the jogger 136 to the vertical flange of the guide 135 is equal to the width of the sheets when the jogger 136 is at its innermost position. Thus sheets of the same width supported by the members 130 (Figure 9) and by the guide 135 and jogger 136 will have their side edges arranged in perfect registration as they approach and engage the gate 71.

At each side of the apparatus is arranged a carriage 165. Each of these carriages, as shown in Figure 9, is shouldered as at 166 to rest upon the adjacent side frame members 42 or 43. Each carriage has an upwardly projecting narrower upper end 167 for a purpose to be described, and adjacent the top of such upper end is arranged a stay rod 168, also serving as a string guide in a manner to be referred to later.

Adjacent their lower ends, the carriages 165 are connected by a second stay rod 170. The stay rods 168 and 170 transversely fix the relative positions of the carriages 165 and render them easily slidable along the side frame members 42 and 43.

The carriages 165 support a rock shaft 172 and this shaft supports a plurality of jogger fingers 173 projecting upwardly between certain adjacent pairs of the paper supporting bars 130, as shown in Figure 9. As will be described, the shaft 172 is rocked to similarly rock the fingers 173, and the carriages 165 are so positioned along the side frame members 42 that the fingers 173 contact the paper sheets, when their forward ends are engaged with the gate 71, thus jogging the sheets longitudinally into perfect registration, the sheets being of the same length.

At one side of the apparatus, preferably adjacent the side frame member 42, the rock shaft 172 carries a crank arm 175. At the upper end of this crank arm is secured a pin 176 (Figures 2 and 9) and this pin is arranged between a pair of collars 177 carried by the rod 146. This rod, therefore, while operating the lateral jogger 136, simultaneously operates the longitudinally effective jogger fingers 173.

Referring to Figure 2, the numeral 180 designates a bearing bracket carried by each of the individual frame members 42 and 43. The bearing brackets 180 rotatably support a string roller 182 (Figure 3) and spaced strings 183 pass around this roll. Extending toward the perforator, the upper runs of the strings 183 extend over the stay rod 168 and thence forwardly and downwardly at a slight angle to a string roller 185 rotatably supported at its ends by the bearings 61 and 62. It will be noted that the string roll 185 is arranged adjacent the shaft 101 (Figure 6). After passing around the roll 185, the lower runs of the strings 183 extend upwardly and rearwardly away from the perforator approximately parallel to the upper runs of the strings. Such lower runs of the strings 183 then pass over a string roll 187 rotatably supported by the carriages 165. The string roll 187 acts as a support for the lower runs of the strings 183, and from the roll 187, the strings extend rearwardly around the roll 182 previously described.

Referring to Figure 3, it will be noted that another set of strings 189 is arranged beneath the strings 183 between the string roll 182 and the carriages 165. As shown in Figure 1, the strings 189 are preferably staggered relative to the strings 183. The strings 189 are employed for conveying successive sheets from the sheet supply means including the vacuum head 47 to the sheet supporting bed comprising the members 130 (Figures 1 and 9).

Each of the strings 189 has the forward end of its upper run 190 extending between the string roll 187 and a rear substantially larger string roll 191 rotatably supported by shafts 192 carried by the bearing brackets 180. The strings 189 pass around the string roll 187 and then extend rearwardly as at 194 to and around a string roll 195 rotatably supported in a manner to be described. After passing around the roll 195, the strings 189 extend forwardly as at 197 and thence around a string roll 198 rotatably supported by the side frame members 42 and 43. After passing around the roll 198, the strings 189 extend rearwardly and upwardly at a slight angle as at 199 to and around the string roll 191, thus completing their circuit.

One arm of the bearing bracket 180 supports a stay rod 200 and this rod carries arms 201 each of which is provided at its rear end with a hold-down rubber or similar roller 202 arranged above the string roll 191. The rollers 202 are freely rotatable and serve to maintain the sheets, entering the apparatus, in contact with the upper runs 190 of the strings 189. Accordingly the positive driving of the string roll 191 causes the upper runs 190 of the strings 189 to feed successive sheets forwardly over the string roll 187 from which the sheets drop to the sheet supporting bed comprising the members 130. It will become apparent that since the plane of movement of the sheets passing over the string roll 187 is above the plane of the tops of the members 130, successive sheets may be fed on to the latter members in overlapping relationship. In a man-

ner to be described, the position of the string roll 187 is adjusted so that the rear end of each successive sheet will drop therefrom very shortly prior to the engagement of the forward edge of such sheet with the gate 71 (Figure 6).

Referring to Figures 3 and 10, it will be noted that the string roller 195 is supported at its ends by stub shafts 210 which rest upon and are supported by the respective side rails 42 and 43. As is true of all of the string rolls, the shafts for supporting the string roll 195 carry the inner members of ball bearings the outer elements of which are carried by the string rolls themselves. Such ball bearings form no part per se of the present invention and accordingly need not be illustrated, but mention is made of the preferred use of ball bearings for the string rollers in order that such rollers may freely rotate.

The stub shafts 210 (Figure 10) extend through blocks 211 which extend below the upper limits of the side frame members 42 and 43 as shown in Figure 3 and are arranged adjacent the inner surfaces of the side frame members. Accordingly the blocks 211 prevent axial movement of the string roller 195 while the stub shafts 210 support such string roller by resting on the side frame members 42 and 43.

Auxiliary side frame members 215 have their inner ends arranged against inner faces of the respective blocks 211 as shown in Figures 3 and 10, above the top of the string roller 195. Such frame members 215 are fixed to the respective blocks 211 by machine screws 216 or any other suitable fastening means. The forward ends of the frame members 215 contact with the inner faces of the respective carriages 165 and are fixed thereto as at 217. Accordingly it will be apparent that the blocks 211, frame members 215 and carriages 165 are fixed together as a unit, and such unit is adjustable longitudinally of the side frame members as described below.

Each block 211 is connected as at 220 to the ends of a chain 221. These chains pass around rear sprockets 222 rotatable on shafts 223 fixed to the side frame members 42 and 43. The chains 221 pass around forward sprockets 225 fixed to a rotatable shaft 226 which extends transversely across the apparatus and is journaled in the side frame members 42 and 43. Outwardly of the side frame member 42, the shaft 226 is provided with a hand wheel 227 whereby the sprockets 225 can be rotated to operate the chains 221 and thus move the blocks 211 longitudinally of the apparatus, such movement being transmitted through the frame members 215 to the carriages 165.

The means employed for supplying successive sheets to the inlet end of the apparatus, that is, from the right hand end as viewed in Figures 2 and 3 and over the string roll 191, forms no part of the present invention and need not be illustrated in detail. Such mechanism may be of the type in common use for supplying successive sheets from the top of a stack by operation of a conventional vacuum head 47, the stack of papers being supported on suitable means having an automatic mechanism associated therewith for feeding the stack upwardly toward the vacuum head 47 as the sheets are fed from the top of the stack. Such mechanism, moreover, may employ the usual power driving means, and any suitable manual power transmission means may be connected therefrom to the shaft 192 (Figure 2) to operate it. This shaft is preferably provided with a sprocket 230 around which passes

a chain 231, and this chain passes around a sprocket 242 formed on the periphery of the disc 35 of the perforator. While this particular drive means for the perforator is not essential to the present invention, its use is preferred in order that the driving of all of the parts forming the present combination of elements may be properly synchronized.

Operation

The paper to be perforated is stacked beneath the vacuum head 47 and supported by the usual mechanism (not shown) for feeding the stack upwardly as successive sheets are fed from the stack by the vacuum head 47. With the device in operation, the perforator will be driven by the chain 231 which, in turn, is driven by the pulley 230. The shaft 192 derives its power in any suitable manner (not shown) preferably from the power means which drives the feed device for the paper supply mechanism associated with the vacuum head 47.

As each successive cam 36 engages the roller 56, the valve 51 will be opened to connect the vacuum head 47 to the source of vacuum. The head 47, constantly rotating, will engage the top sheet of the pack and feed it over the strings 46 and into the present apparatus between the rollers 202 (Figure 3) and string roll 191. The sheet will be held down by the lower runs of the strings 183 while being supported and conveyed by the upper runs 190 of the strings 189.

As the successive sheets approach the string roll 187, their top surfaces will come into engagement with the bottom runs of the strings 183 which pass over the string roll 187. The two sets of strings between which the sheets pass are driven at the same linear speed and the engagement of each sheet between these sets of strings causes the sheet to be positively moved forwardly or to the left as viewed in Figures 2 and 3. After passing over the string roll 187, the sheet will be unsupported and is free to drop down over the supporting bars 130. Obviously, the leading edge of the paper will travel some distance beyond the string roll 187 before dropping into contact with the supporting bars 130, or into contact with the next preceding sheet which may have been fed into collecting position on the bars 130. Therefore, the leading edges of successive sheets will pass beyond the following edge of any preceding sheet and accordingly is free to slide thereover as it is pushed forwardly by the conveying strings 183 and 189.

In this connection it is pointed out that the carriages 165 are adjusted longitudinally along the side rails 42 and 43 to a position in which the jogger fingers 173 (Figure 3), when in their forward positions, will engage the following edges of the sheets while the leading edges are in contact with the gate 71 (Figure 6). Accordingly it will be apparent that as each cam 36 operates the vacuum valve 51, another sheet will be fed to the apparatus and successive sheets will be superimposed on the collecting bed formed by the bars 130.

Continuously during the operation of the apparatus, the eccentric pin 156 (Figure 4) will be rotated by the shaft 100, this shaft being driven through the chain 103 and sprocket 102. The throw of the eccentric pin 156 is obviously relatively slight, and accordingly it operates through the link 158 to constantly reciprocate the rod 142 through a short travel. The bar 148 constantly rocks the two bell crank levers 144 (Figure 1) and these levers, in turn, therefore con-

stantly reciprocate the transverse jogger shafts 140 and 141. Both of these shafts are connected to the transverse jogger rail 136 and accordingly as successive sheets approach the gate 71, the sheets are jogged laterally to register them transversely. As previously stated, the distance between the jogger rail 136 and the guide rail 135 (Figure 9), when the jogger 136 is at its innermost limit of movement is adjusted so that the vertical flanges of the members 135 and 136 will just contact the longitudinal edges of the paper.

The jogger 136 is adjustable along the shafts 140 and 141 by loosening the set screws carried by the associated supporting collars 150. If the sheets are of greater width than that for which the apparatus is adjusted, as shown in Figure 9, the jogger 136 will be adjusted outwardly toward the rail 42 and one or more additional supporting bars 139 will be placed in position and supported by suitable collars 123. If the sheets are narrower, one or more of the supporting bars 139 will be removed.

The longitudinal reciprocation of the bar 148 transmits movement through the collars 177 (Figures 1 and 9) to the crank arm 175 to rock the shaft 172 and thus transmit similar movement to the longitudinal jogger fingers 173. As previously stated, the carriages 165 are adjusted along the rails 42 so that the jogger fingers 173 will contact with the following edges of the sheets when the fingers 172 are at their limits of movement toward the left, as viewed in Figure 3, with the leading edges of the sheets in engagement with the gate 71. The successive sheets are thus jogged longitudinally by the fingers 173 while being jogged laterally by the rail 136, and accordingly the collected sheets are placed in perfect registration with each other.

The number of sheets collected in the manner described depends upon the nature and thickness of the sheets. As previously stated, the conventional rotary perforator with which the present apparatus is particularly intended to be used perforates sheets, and particularly paper sheets, far more cleanly if a plurality of sheets are fed through the perforator at each operation thereof. The number of sheets thus gathered is accordingly determined in accordance with the nature and thickness of the sheets and the proper number of cams 36 is arranged in position.

In the present instance, five of the cams 36 have been illustrated, and accordingly five sheets will be gathered for each perforating operation. In such case, the cams will be arranged 60° apart, thus leaving a gap 38 (Figure 2) of 120°. After the last cam 36 for a given rotation of the perforating discs has taken place, five sheets will have been gathered ready for the perforating operation, and at this point, the gap 38 approaches the roller 56 and one operation of the rod 53 will be skipped and no sheet will be fed to the apparatus by the vacuum head 47.

At this point, the cutaway 31 (Figure 4) will reach the adjacent end of the rod 86 and such end of this rod will be free to move upwardly under the influence of the spring 77 (Figure 8) exerting a turning force on the arm 76. Thus the shaft 70 will be rocked together with the gate 71 to free the collected sheets for movement over the bed 27 of the perforator.

The operation referred to rocks the shaft 70 in a counterclockwise direction as viewed in Figure 8 and in a clockwise direction as viewed in Figure 6. The rocking of the shaft 70 (Figure 6)

swings the gate 71 in a counterclockwise direction and at the same time rocks the two discs 115 in the same direction and the shoulders 113 will move downwardly away from the screws 116. 5 This operation permits the lowering of the free ends of the bearing arms 110 to similarly lower the rubber or similar rollers 120. The screws 116 follow the shoulders 113 in their downward movements until the rollers 120 contact with the sheets resting on the roller shaft 100. When this 10 point in the operation is reached, the constantly rotating roller shaft 100, by virtue of the weight of the rollers 120 and associated parts on the pack of sheets, will cause the sheets to start to move toward the left as viewed in Figure 6. At this point, the gate 71 will have moved toward the left free of the leading edges of the sheets and accordingly the latter may move past the gate.

20 While the rollers 120 remain in contact with the uppermost gathered sheet, the gate 71 continues to turn until the arm 76 (Figure 8) contacts with the rubber bumper 89 to limit further turning movement of the shaft 70. At such point, 25 the gate 71 will be opened sufficiently to permit the free passage of the sheets toward the perforator. The sheets continue to advance under the propelling force exerted by the roller shaft 100 and rollers 120 until the sheets are firmly engaged by the perforator feed rollers 24 and 25 and these rollers thereafter positively pull the sheets from the collecting mechanism to feed them to and between the perforator discs 16 and 18.

30 Promptly upon the positive engagement of the sheets between the rollers 24 and 25, the free end of the rod 86 (Figure 4) passes relatively beyond the other end of the cutaway 31, whereupon the rod 86 will be rocked back to its normal position and the shaft 70 will be rotated against the tension of the spring 77 to return the gate 71 to its normal closed position.

35 Particular attention is invited to the fact that the bottom edge of the gate 71, when in the normal position shown in Figure 6, lies approximately in, and definitely not above, the horizontal plane of the top of the bed 27 and block 64 (Figure 6). Thus successive sheets fed on to the collecting bed will have their forward edges brought definitely into engagement with the gate 71 to arrest forward movement of the sheets when the gate is closed and the sheets are being fed thereto. However, the inclined surface 67 provides a space between such surface and the lower 40 edge of the gate 71 when the latter is in closed position. Thus the gate is permitted to close as soon as a collection of sheets have had their forward edges engaged by the rollers 24 and 25, and the sheets will be positively pulled toward the 45 perforator while passing beneath the gate 71. The sheets will be merely bowed downwardly as 50 they pass beneath this gate.

55 The feature of the apparatus just described is highly important in producing an efficient and rapid feeding of sheets to the perforator. Just as soon as the gate 71 has closed, the first following sequence of operations of the vacuum valve 51 takes place by engagement of the first cam 36 with the roller 56. The gap provided at 60 the point 38 (Figure 2) is for the purpose of initiating the feeding of a collection of sheets to the perforator. The supplying of sheets to the collecting mechanism is resumed in the manner described just as soon as the advancing edges 65 of the sheets are engaged by the rollers 24 and

25 and at such point, the following edges of the sheets will have advanced only a short distance beyond the vertical plane of the string roll 187 (Figure 3). Since the sheets are fed to the collecting bed at a point substantially above the horizontal plane of the latter, the first sheet of the next succeeding collection will be fed forwardly over and will drop down upon the top sheet of the previous collection now being pulled forwardly by the feed rolls 24 and 25.

Accordingly it will be apparent that as soon as movement of a collection of sheets toward the perforator has been started, the collection of the next group of sheets is initiated without awaiting the clearing of the sheets moving toward the perforator. Accordingly the apparatus functions to feed a collection of sheets to the perforator for each successive complete rotation of the perforator discs 16 and 18. Thus the apparatus has the advantage of being fully automatic in operation and of providing a rapid production rate. As a matter of fact, the apparatus has been found in practice to have a rate of production approximately four times that of the hand feeding of perforators, as now generally practiced in the industry.

The adjustment of the transverse and longitudinal jogging means for sheets of different sizes has been previously described, at least in a general way, as to the positioning of the jogger fingers 173. These fingers are movable with the carriages 165, and these carriages are moved along the side rails 42 and 43 by operating the hand wheel 227. Rotation of this hand wheel in a clockwise direction, as viewed in Figure 2, advances the carriages 165, frame members 215, blocks 211 and string roller 195 toward the left, and this is the adjustment which will take place when shorter sheets are to be fed through the apparatus. It will be apparent that the string rollers 187 and 195, under such conditions, will be bodily moved as a unit and the elongation of the upper runs 190 of the strings 189 will be exactly compensated for by the forward movement of the string roll 195. The reverse operation takes place where longer sheets are to be fed through the apparatus, as will be apparent, it merely being necessary to rotate the hand wheel 227 in a clockwise direction.

From the foregoing, it will be apparent that the present apparatus is fully automatic for collecting sheets fed singly thereto until a predetermined number of sheets has been collected, and to then promptly release such collection of sheets and feed them to the perforator. It also will be apparent that promptly upon the starting of one group of sheets toward the perforator, the apparatus automatically initiates the collection of the next succeeding group of sheets. The apparatus also functions to jog the sheets automatically to perfectly align them as they are collected, and accordingly all of the normally hand-performed functions in an apparatus of this character are rapidly, automatically and accurately performed, and the elimination of hand gathering and feeding renders the apparatus highly economical in operation.

I claim:

1. A sheet feeding apparatus comprising a sheet collecting bed, a gate at one end of said bed, means for supplying successive sheets to said bed from the opposite end thereof, said gate normally occupying an operative position in the path of travel of the advancing edges of such sheets to arrest the successive sheets in superimposed relation, a constantly driven roller ar-

ranged beneath the sheets on said bed, a roller arranged above said first named roller and normally out of contact with the sheets on said bed, and means for substantially simultaneously moving said gate to open position above the level of the sheets on said bed and for dropping said second named roller into contact with the sheets whereby said first named roller becomes effective for feeding the sheets from said bed beneath said gate, said rollers being the sole means for moving the sheets from said bed.

2. A sheet feeding apparatus comprising a horizontal sheet collecting bed, means for supplying successive sheets to said bed from one end thereof, said sheet supplying means being arranged substantially above the level of said bed whereby each sheet fed to the latter will pass over the top of the preceding sheet, a gate at the opposite end of said bed for arresting movement of the successive sheets in a position with their leading edges substantially in vertical alignment, a roller arranged beneath the plane of said bed and engageable with the lowermost sheet thereon, said roller extending transversely of the direction of the movement of the sheets supplied to said bed and being constantly driven, a pivoted arm above said bed, a roller carried by said arm and biased for downward movement into engagement with the uppermost sheet on said bed, mechanical means connecting said gate to said arm to normally hold said last named roller out of engagement with the sheets, and means operative upon the gathering of a predetermined number of sheets on said bed for opening said gate and for releasing said arm for movement of said last named roller into engagement with the uppermost sheet to effect frictional engagement of the lowermost sheet with said first named roller whereby the latter moves the collected sheets from said bed past said gate, said rollers being the sole means for moving the sheets from said bed.

3. A sheet feeding apparatus comprising a horizontal bed, means for supplying successive sheets to said bed from one end thereof, a normally closed gate at the other end of said bed for arresting movement of the sheets with the leading edges thereof substantially in vertical alignment, said gate, when closed, having its lower edge projecting downwardly at least past the lowermost sheet on said bed, a surface beneath said gate and spaced therefrom when said gate is in closed position, means operative after a predetermined number of sheets have been gathered on said bed for rendering said sheet supplying means inoperative and for opening said gate, sheet discharging means controlled by said gate and rendered operative upon the movement thereof to open position for discharging the sheets from said bed beneath said gate, means engageable with the sheets after the leading edges thereof have advanced a predetermined distance beyond said gate for pulling the sheets from said bed, means operative after the sheets have been engaged by said last named means for moving said gate to closed position, the space between said gate and said surface being sufficient for the movement of such sheets beneath said gate after the latter has closed, and means for restoring the operativeness of said sheet supplying means when said gate returns to closed position whereby collection of the next succeeding group of sheets may be started before the preceding group of sheets has been removed from said bed.

4. A sheet feeding apparatus comprising a

horizontal bed, means for supplying successive sheets to said bed from one end thereof and in superimposed relationship thereon, a rock shaft extending over the opposite end of said bed, a depending gate carried by said shaft and arranged in the path of travel of the sheets for arresting movement of the sheets with the leading edges thereof substantially in vertical alignment, and means operative after a predetermined number of sheets have been gathered on said bed for rocking said shaft to open said gate and release the sheets for movement from said bed beneath said gate, said bed having a portion just in advance of said gate slightly higher than the portion beneath said gate, said latter portion of said bed being spaced below said gate when the latter is in operative position whereby, upon return movement of said gate to operative position, the sheets leaving said bed are free to pass beneath said gate.

5. A sheet feeding apparatus comprising a horizontal bed, means for supplying successive sheets to said bed from one end thereof in superimposed relationship, a rock shaft extending over the opposite end of said bed, a gate carried by said shaft and normally depending therefrom in an operative position engageable with the leading edges of successive sheets to arrest movement of the sheets, means biasing said shaft for turning movement to tend to open said gate, and means operative after a predetermined number of sheets have been gathered on said bed for releasing said biasing means to rock said shaft to open said gate and release the sheets for movement from said bed beneath said gate, said bed having a portion just in advance of said gate slightly higher than the portion beneath said gate, said latter portion of said bed being spaced below said gate when the latter is in operative position whereby, upon return movement of said gate to operative position, the sheets leaving said bed are free to pass beneath said gate.

6. A sheet feeding apparatus comprising a horizontal bed, means for supplying successive sheets to said bed from one end thereof in superimposed relationship, a rock shaft extending over the opposite end of said bed, a gate carried by said shaft and normally depending therefrom in an operative position engageable with the leading edges of successive sheets to arrest movement of the sheets, means biasing said shaft for turning movement to tend to open said gate, an arm carried by said shaft, and a cam device having a portion normally engaging said arm to hold said gate in normal position, said cam device having a portion movable into cooperative relationship with said arm to release the latter and thus release said rock shaft whereby said biasing means turns said shaft to open said gate and release the sheets for movement from said bed beneath said gate, said bed having a portion just in advance of said gate slightly higher than the portion beneath said gate, said latter portion of said bed being spaced below said gate when the latter is in operative position whereby, upon return movement of said gate to operative position, the sheets leaving said bed are free to pass beneath said gate.

7. A sheet feeding apparatus comprising a horizontal bed, means for supplying successive sheets to said bed from one end thereof in superimposed relationship, a rock shaft extending over the opposite end of said bed, a gate carried by said shaft and normally depending therefrom in an operative position engageable with the leading edges of successive sheets to arrest move-

ment of the sheets, means biasing said shaft for turning movement to tend to open said gate, an arm carried by said shaft, a rotary member having a concentric portion engageable with said arm to hold said shaft in a position with said gate in said normal position throughout the greater portion of each rotation of said rotary member, said rotary member having a cut-out portion in which said arm drops after a predetermined number of sheets have been gathered on said bed for releasing said shaft for movement by said biasing means to open said gate whereby said sheets are movable from said bed beneath said gate, said bed having a portion just in advance of said gate slightly higher than the portion beneath said gate, said latter portion of said bed being spaced below said gate when the latter is in operative position whereby, upon return movement of said gate to operative position, the sheets leaving said bed are free to pass beneath said gate.

8. A sheet feeding apparatus comprising a horizontal bed, means for supplying successive sheets to said bed from one end thereof in superimposed relationship, a rock shaft extending over the opposite end of said bed, a gate carried by said rock shaft and normally depending therefrom to an operative position engageable with the leading edges of said sheets to arrest movement of the sheets with the leading edges thereof in vertical alignment, means biasing said gate to open position, an arm carried by said rock shaft, a cam device engaging said arm to hold said gate in said normal position and having a portion movable into cooperative relationship with said arm to release it whereby said biasing means swings said gate away from the leading edges of the sheets to open position, and means operative upon the opening of said gate for engaging the sheets on said bed and moving them therefrom beneath said gate, said bed having a portion just in advance of said gate slightly higher than the portion beneath said gate, said latter portion of said bed being spaced below said gate when the latter is in operative position whereby, upon return movement of said gate to operative position, the sheets leaving said bed are free to pass beneath said gate.

9. Apparatus constructed in accordance with claim 8 wherein the means for feeding the sheets from said bed comprises a pair of pinch rolls one of which normally engages the lowermost sheet on said bed and the other of which is normally arranged above the uppermost sheet on said bed, means for constantly driving said lower roller, and means operative upon the opening of said gate for releasing said upper roller for downward movement into engagement with the uppermost sheet on said bed.

10. A sheet feeding apparatus comprising a horizontal bed, sheet supplying means arranged adjacent one end of said bed and projecting therefrom above the horizontal plane thereof for feeding successive sheets to said bed, a rocking member projecting horizontally across the opposite end of said bed, a gate carried by said rocking member and normally depending therefrom in an operative position for engaging leading edges of the successive sheets for arresting their movement with such leading edges in vertical alignment, said gate having a space therebeneath when in closed position, means operative after a predetermined number of sheets have been gathered on said bed for opening said gate, sheet moving means engageable with sheets on said bed when said gate is opened for effecting movement of the

sheets beneath said gate, means engageable with the sheets to continue their movement from said bed after the leading edges of the sheets have passed beyond said gate, means operative after the sheets have been engaged by the last named sheet moving means for returning said gate to closed position, and means operative upon the closing of said gate for releasing said first named sheet moving means from operative engagement with the sheets on said bed.

11. Apparatus constructed in accordance with claim 10 provided with means for arresting the supplying of sheets to said bed when said gate is opened and for resuming the supplying of successive sheets upon the closing of said gate whereby successive sheets for the next group will be fed to said bed before the preceding group has been removed therefrom.

12. Apparatus constructed in accordance with claim 10 wherein said sheet supplying means comprises a vacuum feeding head, and a plurality of cams successively operative for rendering said vacuum head operative to supply said successive sheets, said cams having a gap therein synchronized with the opening of said gate whereby the supplying of successive sheets will be momentarily arrested until movement of each group of sheets from said bed has been initiated and said gate has returned to closed position.

13. In combination with a rotary sheet perforator having rotary coacting perforating discs and a pair of sheet feeding pinch rolls arranged at the inlet side of said discs for feeding paper into engagement therewith, a sheet collecting bed, means operative in predetermined synchronism with the rotation of said discs for supplying successive sheets to said bed in superimposed relationship from the end of said bed remote from said perforator, a gate arranged over said bed at the end thereof adjacent said perforator, said gate having a normal closed position in the path of travel of the sheets to arrest movement thereof with their leading edges in vertical alignment, and means operative once during each rotation of said discs for opening said gate for the release of sheets from said bed, and means operative to move the released sheets from the bed into engagement with said pinch rolls which feeds the sheets to the perforating discs.

14. In combination with a rotary sheet perforator having rotary coacting perforating discs and a pair of sheet feeding pinch rolls arranged at the inlet side of said discs for feeding paper into engagement therewith, a sheet collecting bed, means operative in predetermined synchronism with the rotation of said discs for supplying successive sheets to said bed in superimposed relationship from the end of said bed remote from said perforator, a gate arranged over said bed at the end thereof adjacent said perforator, said gate having a normal closed position in the path of travel of the sheets to arrest movement thereof with their leading edges in vertical alignment, and means operative once during each rotation of said discs for opening said gate, and means operative upon the opening of said gate for initiating movement of the sheets from said bed past the said gate and into engagement with said pinch rolls which feeds the sheets to the perforating discs.

15. In combination with a rotary sheet perforator having rotary coacting perforating discs and a pair of sheet feeding pinch rolls arranged at the inlet side of said discs for feeding paper into engagement therewith, a sheet collecting bed,

means operative in predetermined synchronism with the rotation of said discs for supplying successive sheets to said bed in superimposed relationship from the end of said bed remote from said perforator, a gate arranged over said bed at the end thereof adjacent said perforator, said gate having a normal closed position in the path of travel of the sheets to arrest movement thereof with their leading edges in vertical alignment, and means operative once during each rotation of said discs for opening said gate, a pair of sheet-moving rolls within the area of said bed, one below said bed in contact with the lowermost sheet thereon and the other above said bed and normally supported by said gate out of engagement with the uppermost sheet on said bed, the lower of said rolls being constantly driven and the upper of said rolls being releasable by movement of said gate to open position for downward movement into engagement with the uppermost sheet on said bed, said gate opening means being operative for maintaining the gate in open position only until the leading edges of the collected sheets have been engaged by said pinch rolls which feeds the sheets to the perforating discs.

16. A sheet feeding apparatus comprising a sheet collecting bed, means for supplying successive sheets to said bed in superimposed relationship from one end thereof, a gate adjacent the opposite end of said bed and normally occupying a position in the path of travel of the sheets to engage the leading edges of the successive sheets to arrest movement of the sheets, said bed being cut away beneath said gate to provide a space at least coextensive in length to the leading edges of the sheets, means for moving said gate to an inoperative position above the level of the sheets, means operative when said gate moves into inoperative position for advancing the sheets past said gate, means beyond said gate engageable with the sheets after they pass said gate, and means for returning said gate to normal position upon engagement of said last-named means with the sheets, the space beneath said gate when the latter is in operative position being at least equal in thickness to the collected sheets for the passage of the latter through said space while said gate is in operative position.

17. In combination with a sheet working apparatus having a device for performing work on thin flexible sheets, and having sheet feeding pinch rolls adjacent the inlet side of the apparatus for engaging sheets fed thereto and moving such sheets into engagement with said device, a sheet collecting bed at the inlet side of said sheet working apparatus, means for feeding successive sheets to said bed in superimposed relationship from the end of said bed remote from said sheet working apparatus, a gate arranged over said bed adjacent the opposite end thereof, said gate being mounted to swing on a horizontal axis spaced above said bed and above the lower edge of said gate for swinging movement inwardly and upwardly toward the sheet working apparatus, said gate normally occupying a position engageable with the leading edges of the successive sheets to arrest movement of the sheets with such leading edges in vertical alignment, and means operative after a plurality of sheets of a predetermined number have gathered on said bed for opening said gate and moving the collected sheets past said gate into engagement with said pinch rolls.

18. A sheet feeding apparatus comprising a col-

lecting bed, a gate at one end of said bed, means for conveying sheets to said bed from the other end thereof, means at the end of said conveying means remote from said bed for supplying sheets to said conveying means in overlapping relationship, said gate normally depending toward said bed and being spaced therefrom for the passage of sheets beneath said gate, said bed just in advance of said gate having a portion at least as high as the bottom of said gate whereby incoming sheets will have their leading edges at such height as to be engaged by said gate to have their movement arrested thereby, means for opening said gate after a plurality of sheets to a predetermined number have collected at said gate, means operative upon operation of said last-named means for advancing the collected sheets past said gate, and means for closing said gate before the next successive sheet from said conveying means reaches said gate.

19. A sheet feeding apparatus comprising a collecting bed, a gate at one end of said bed, means for conveying sheets to said bed from the other end thereof, means at the end of said conveying means remote from said bed for supplying sheets to said conveying means in overlapping relationship, said gate normally depending toward said bed and being spaced therefrom for the passage of sheets beneath said gate, said bed just in advance of said gate having a portion at least as high as the bottom of said gate whereby incoming sheets will have their leading edges at such height as to be engaged by said gate to have their movement arrested thereby, means for opening said gate after a plurality of sheets to a predetermined number have collected at said gate, means operative upon operation of said last-named means for advancing the collected sheets past said gate, means beyond said gate for engaging the advancing edges of sheets passing beneath said gate for pulling the collected sheets therebetween, and means for closing said gate before the next successive sheet from said conveying means reaches said gate.

20. A sheet feeding apparatus comprising a sheet collecting bed, a stop member at one end of said bed, means for feeding successive sheets over said bed toward said stop member, said stop member being normally arranged in an operative position to engage the leading edges of said sheets and arrest movement of the sheets, normally inoperative means for moving collected sheets from said bed, means operative after a predetermined number of sheets have been collected on said bed for moving said stop member to an inoperative position out of engagement with the sheets, means operative upon the moving of said stop member to inoperative position for rendering said sheet moving means operative for engaging the sheets and feeding them from said bed, and means operative to return said stop member to operative position to contact the leading edge of a succeeding sheet while said collected sheets are being fed from said bed and before the trailing edges thereof have passed by said stop member.

21. A sheet feeding apparatus comprising a sheet collecting bed, a stop member at one end of said bed, means for feeding successive sheets over said bed toward said stop member, said stop member being normally arranged in an operative position to contact the leading edges of said sheets and arrest movement of the sheets, normally inoperative pinch rolls arranged respectively above and below the sheets on said bed, means operative after a predetermined number of sheets

have been gathered on said bed for moving said stop member to an inoperative position out of engagement with said sheets, and means operative in response to movement of said stop member to inoperative position for effecting operative engagement of said pinch rolls with the collected sheets for moving them from said end of said bed.

22. A sheet feeding apparatus comprising a sheet collecting bed, a gate at one end of said bed, means for supplying successive sheets to said bed from the opposite end thereof, said gate normally occupying an operative position in the path of travel of the advancing edges of such sheets to arrest the successive sheets in superimposed relation, means operative after a predetermined number of sheets have been collected on said bed for moving said gate to a position above the level of the collected sheets for the discharge of the sheets from said bed beneath said gate, means operative to feed the collected sheets from the bed when said gate is thus moved, and means operative to return said gate to operative position to contact the leading edge of a succeeding sheet while said collected sheets are being fed from said bed and before the trailing edges thereof have passed by said gate.

23. A sheet feeding apparatus comprising a sheet collecting bed, a gate at one end of said bed, means for supplying successive sheets to said bed from the opposite end thereof, said gate normally occupying an operative position in the path of travel of the advancing edges of such sheets to arrest the successive sheets in superimposed relation, means providing a space beneath said gate when in closed position, means supporting said sheets so that the leading edges thereof contact said gate when in closed position, normally inoperative sheet discharging means adjacent said bed, and means for substantially simultaneously moving said gate to open position above the level of said sheets and for rendering said sheet discharging means operative for moving the sheets from said bed beneath said gate.

24. A sheet feeding apparatus comprising a sheet collecting bed, means for supplying successive sheets to said bed from one end thereof, a gate at the opposite end of said bed for arresting movement of the successive sheets in a position with their leading edges substantially in vertical alignment, a roller arranged beneath the plane of said bed and engageable with the lowermost sheet thereon, said roller extending transversely of the direction of the movement of the sheets supplied to said bed, means for driving said roller, a pivoted arm above said bed, a roller carried by said arm and biased for downward movement into engagement with the uppermost sheet on said bed, mechanical means connecting said gate to said arm to normally hold said last named roller out of engagement with the sheets, and means operative upon the gathering of a predetermined number of sheets on said bed to open said gate and to release said arm for movement of said last named roller into engagement with the outermost sheet to effect frictional engagement of the lowermost sheet with said first named roller whereby the latter moves the collected sheets from said bed past said gate.

25. In combination with a rotary sheet perforator having rotary coating perforating discs and a pair of sheet feeding pinch rolls arranged at the inlet side of said discs for feeding paper into engagement therewith, a sheet collecting bed, means operative in predetermined synchronism with

the rotation of said discs for supplying successive sheets to said bed in superimposed relationship from the end of said bed remote from said perforator, said means comprising a plurality of spaced cams driven with said discs, a gate arranged over said bed at the end thereof adjacent said perforator, said gate having a normal closed position in the path of travel of the sheets to arrest movement thereof with their leading edges in vertical alignment, means operative once during each rotation of said discs for opening said gate for the release of sheets from said bed, and means operative to move the sheets from said bed into engagement with said pinch rolls which feed the sheets to the perforating disc, a pair of said cams being substantially spaced to provide a gap therebetween synchronized with the opening of said gate whereby the supplying of successive sheets is interrupted momentarily in synchronism with the opening of said gate.

ROBERT J. THOMPSON.
